UNITED STATES PATENT OFFICE.

JOHN ERICK LINDEN, OF DULUTH, MINNESOTA.

SPOOL FOR PHOTOGRAPHIC FILMS.

1,261,946.

Specification of Letters Patent. Patented Apr. 9, 1918.

Application filed May 7, 1917. Serial No. 166,938.

To all whom it may concern:

Be it known that I, JOHN E. LINDEN, a citizen of the United States, residing at Duluth, in the county of Saint Louis and State of Minnesota, have invented certain new and useful Improvements in Spools for Photographic Films; and I do declare the following to be a full, clear, and exact description of the invention, such as will enable others skilled in the art to which it appertains to make and use the same.

This invention relates to certain new and useful improvements in spools used primarily in photography for winding films thereon.

One object of the invention is to provide a spool which may be formed from a single piece of material, preferably sheet metal, thus making the spool very light and a rather inexpensive article.

Another object of the invention is to provide a spool designed particularly for holding films, the spool being provided with an improved means for securing one end of the film thereto.

A further object of the invention is to generally improve upon devices of this class by the provision of an extremely simple, strong, and durable construction, one which will be efficient and reliable in operation, and well adapted to the purpose for which it is designed.

With these and other objects in view, the invention consists of certain novel features of construction, and the combination and arrangement of parts as will be hereinafter fully described and claimed.

In the accompanying drawing forming a part of the application, and in which similar reference characters designate like parts throughout the several views:

Figure 1 is a plan view of a blank from which one of the improved spools may be formed.

Fig. 2 is a side elevation of one of the spools;

Fig. 3 is a longitudinal sectional view thereof;

Fig. 4 is a transverse sectional view taken on the plane indicated by the line 4-4 of Fig. 3; and

Fig. 5 is a similar view taken on the plane indicated by the line 5-5 of Fig. 2.

Referring more particularly to the drawing, the numeral 1 designates a split tubular stem having overlapping edges as shown,

and being of a length substantially equal to the width of the film which it is designed to carry. Extending outwardly from the ends of the stem and spaced from the edges thereof are lugs 2 and connected to these lugs 2 and folded in superposed relation therewith are circular head members 3, the edges of which are crimped inwardly as at 4 around the free ends of an additional pair of lugs 5 which extend outwardly from the ends of the stem 1 adjacent one of its edges. The lugs 2 form the means for integrally connecting the head members 3 to the stem 1, while the lugs 5 are in effect braces for preventing said head members from being easily bent out of place. The lugs 2 and 5 extending in opposite directions and being disposed upon opposite sides of the stem 1, provide a rather rigid mounting of the head members with respect to the stem.

One edge of the stem 1, preferably the innermost edge, is provided with a shallow notch 6 to form a longitudinally extending slot in the stem for the reception of one end of the backing strip carrying the film. This backing sheet, designated by the letter *a*, being of comparatively heavy and stiff paper, has a tendency not to be folded sharply or creased, and hence when it is inserted in the slot in the spool, it will engage the edges of the slot and will offer much resistance toward being removed after the backing strip is wound about a half a turn or more around the stem 1. The strip *a*, however, can be readily and easily disconnected from the spool by unwinding it completely and pulling it transversely out of the slot. The biting action only takes place when the strip is bent around the outer edge of the stem.

One of the head members 3 is provided with a centrally arranged circular opening 7 which is adapted to receive the pivot stud in an ordinary folding camera, while the other head member is provided with an elongated opening 8 adapted to receive the shank portion of the film winding key of the camera.

While the invention is primarily intended for use in connection with the art of photography, for holding roll films, yet it is obvious that the spool construction may be utilized for numerous other purposes, and hence it is to be understood that I do not wish to limit the use of the invention in any manner.

Numerous changes in form, proportion, and in the minor details of construction may be resorted to without departing from the spirit of the invention, and I therefore do not wish to be limited to the precise construction herein shown and described.

I claim:

A spool formed from a single piece of material comprising a tubular split stem having overlapping edges, the innermost edge having a shallow notch therein to provide said stem with a longitudinally extending slot, outwardly extending lugs formed at the ends of said stem and spaced from the edges thereof, head members integrally

united with said lugs and folded in superposed relation thereon, and additional outwardly extending lugs formed at the ends of said stem and disposed adjacent one edge thereof, the edges of said head members being crimped inwardly around the free ends of the last mentioned lugs. 20

In testimony whereof I have hereunto set my hand in the presence of two subscribing witnesses.

JOHN ERICK LINDEN.
